A technical line drawing of a mechanical assembly. It features a central rectangular frame with diagonal bracing. Inside the frame, there are several horizontal and vertical components, including a central vertical rod and a horizontal beam. The drawing is annotated with numbers: '6' and '9' are at the top left; '7' is on the left side; '24' is on the left; '22' is on the left; '2' is on the left; '13' is on the left; '13a' is on the left; '16' is at the bottom left; '6' is at the bottom center; '12' is at the bottom center; '13a' is at the bottom center; '23' is at the bottom center; and '6' is at the bottom right. The entire assembly is set against a background with diagonal hatching.

UNITED STATES PATENT OFFICE.

BARTHOLOMEW PEISEN, OF ELDORA, IOWA.

BICYCLE-SUPPORT.

SPECIFICATION forming part of Letters Patent No. 623,421, dated April 18, 1899.

Application filed January 7, 1899, Serial No. 701,496. (No model.)

To all whom it may concern:

Be it known that I, BARTHOLOMEW PEISEN, a citizen of the United States, residing at Eldora, in the county of Hardin and State of Iowa, have invented certain new and useful Improvements in Bicycle-Supports; and I do hereby declare the following to be a full, clear, and exact description of the invention, such as will enable others skilled in the art to which it appertains to make and use the same.

This invention relates to improvements in bicycle-supports; and its object is to provide a support which can be readily and conveniently adjusted for application to bicycle-frames of different sizes and embodies simple and effective means for automatically projecting and spreading the supporting-legs, together with improved devices for closing and folding the legs and also holding the same in a closed position.

A further object is to provide an improved construction of casing, a spring-actuated shaft inclosed therein and acting on the legs to project them, a pivoted lever for closing the legs against the tension of said spring mechanism through the medium of suitable connections and designed to act also as a brake to prevent forward movement of the bicycle, and a holder adapted to be opened and closed automatically to engage and release the legs when said connections are operated.

With these and other objects in view the invention consists in certain novel features of construction, combination, and arrangement of parts, which will be hereinafter more fully described, and particularly pointed out in the appended claims.

In the accompanying drawings, forming a part of this specification, Figure 1 is a fragmentary perspective view of a bicycle supported in an upright position by means of my invention. Fig. 2 is a fragmentary side elevational view of a bicycle, showing the parts of the support closed. Fig. 3 is a top plan view of the casing with cover removed, showing the position of the parts when the legs are projected. Fig. 4 is a similar view showing the position of the parts when the legs are closed or folded up. Fig. 5 is a longitudinal sectional view of the casing with the parts arranged as shown in Fig. 4. Fig. 6 is a cross-sectional view thereof with the parts arranged as shown in Fig. 3.

Fig. 7 is a cross-section through the flexible rod 24, showing the holder or rest for supporting the legs in rear elevation. Fig. 8 is 55 a front perspective view showing the pivoted supporting members and confining-plate of the holder or rest detached, but in their relative positions. Fig. 9 is a detail perspective view of the pivoted lever and connecting-links. Fig. 10 is a detail sectional view of the head-clamp and lever. Fig. 11 is a detail sectional view of the clips shown in Figs. 7 and 8. Fig. 12 is a similar view of one of the supporting-legs. 65

Referring now more particularly to the drawings, wherein like reference-numerals designate corresponding parts throughout the several views, 1 represents the lower main tube of a bicycle-frame, and 2 a casing closed 70 at top by a cover 3, having its upper surface concaved to closely embrace the said tube and provided with clips 4, whereby it is connected therewith a short distance in advance of the crank-hanger. The casing is provided 75 with a curved or segment-shaped bottom 5, provided on opposite sides of its center with substantially S-shaped slots 6, extending longitudinally thereof, and the front ends of these slots are curved inwardly toward each 80 other, while their rear ends are curved outwardly or diverge toward the sides of the casing, as shown clearly in Figs. 3 and 4.

Arranged within the casing is an oscillatory shaft or arbor 7, provided with journals 85 or trunnions journaled in the side walls thereof or in suitable bearings secured upon the inner sides thereof. This shaft or arbor is held under tension by strap or ribbon springs 8, provided at their front ends with coils 9, 90 embracing the opposite ends of said shaft and suitably secured thereto and having their opposite ends 10 extended rearwardly and passed over a post or cross-bar 11, connecting the sides of the casing, so that said free ends 95 will bear against the rear walls of the casing and be held against displacement. Arranged also in the casing are a pair of substantially U-shaped oscillatory frames 12, having their outer arms 13 extended and rigidly connected 100 with the shaft or arbor and their inner arms provided with ears 14, connected to similar ears projecting from a tubular head or sleeve 15, rigidly secured to the central portion of

the shaft. To these ears 14 are pivoted the rear ends of a pair of supporting-legs 16, which project through and are adapted to move in the said curved slots 6 and also to move laterally in slots 13^a, formed in the front ends or cross-bars of the U-shaped oscillatory frames. These legs may be either tubular or solid, but in the present instance are shown as provided in their outer ends with threaded sockets 17 for the reception of threaded rods 18, which are adapted to be adjusted to lengthen the legs through the medium of milled thumb-nuts 19 and are provided at their outer ends with knobs or heads 20, having spurs or projections adapted to engage the pavement or ground to prevent the legs from slipping. The strap-springs 8 normally serve to exert a backward pull or tension on the shaft or arbor, which causes it to turn forwardly in the direction of the arrow shown in Fig. 5, and as the U-shaped frame to which the legs are pivotally connected is rigidly secured thereto it will be seen that the legs will be drawn downwardly and outwardly and caused to traverse the slots 6 and that they will be guided by said slots and caused to diverge or spread outwardly, so as to bear upon the surface of the street or ground on opposite sides of the frame of the bicycle, and thus afford a firm and stable support for the latter. It will also be seen that when the legs are fully projected they incline forwardly, and thus tend to hold the bicycle against casual movement in a forward direction.

35 The U-shaped oscillatory frames are connected at their lower ends by a cross bar or rod 21, and mounted on this rod between the frames is a slotted cam or eccentric link 22. The outer surface of this link is grooved or recessed to receive the rear hooked end 23 of a flexible rod 24, which projects outwardly through an opening in the front of the casing and is adapted to slide over a pulley 25, journaled therein. This rod is threaded from a point about midway of its length to its outer end, and this threaded portion projects through an internally-threaded tube 26, supported at its front end by a clip 27, engaging the lower main tube 1 of the frame a short distance in rear of the head-tube thereof. The base portion of this clip is provided with a guide-opening 28, in which the tube is slidably mounted, and is provided at its rear with a detachable confining-plate 30, having forwardly-projecting stops 31 at its ends. Mounted on the tube in rear of said clip is a rest or holder, which supports the free ends of the legs and consists of two members 32 and 33, concaved to form shoulders 32' and 33', upon which the legs are adapted to rest, and provided with ears 34, by which they are pivotally mounted on the tube to move toward and from each other. The said members are also provided with stop-lugs 35, adapted to engage the stops 31 to limit their outward movement and also to engage the confining-plate 30, by which they are held connected

with the clip and are adapted to move therewith. The tube is provided in rear of the clip and holder with a substantially V-shaped trip or striker-wedge 36, which automatically operates to open and close the two members of the holder in the manner hereinafter described.

70 The front end of the tube is threaded externally, as at 37, to receive a slide or adjusting device 38, provided with an opening, through which said tube extends, and a milled thumb-nut 38^a, whereby it may be adjusted thereon. This adjusting device bears against 80 the under side of the lower main tube 1 of the frame and is provided at opposite sides with ears 39, to which the rear ends of curved connecting-links 40 are pivoted. To the head-tube of the bicycle-frame is connected a clamp 85 41, provided with pivoted clamping-arms 42, adapted to engage the same, and to the lower end of this clamp is pivoted a lever 43, provided at one end with curved ears or projections 44, to which the front ends of the said link 90 are pivotally connected. The lever is also provided with a threaded guide and socket for the reception of a threaded shank 45, carrying at its outer end a shoe 47 and adapted to be adjusted through the medium of a 95 milled thumb-nut 48.

90 In Fig. 2 of the drawings I have shown the parts of the support closed or folded up, and from this it will be seen that the pivoted lever is turned to bear against the front surface of the head-clamp. When it is desired to employ the support for supporting the bicycle when the latter is not in use, the pivoted lever is thrown downward and the threaded flexible rod and the guide-tube 105 mounted thereon are forced rearwardly, thus allowing the strap-springs 8, acting on the shaft to which the U-shaped frame and supporting-legs are connected, to force the latter downwardly and rearwardly, whereby the 110 legs are also forced downwardly and are caused by the contour of the slots in the bottom of the casing to spread outwardly as they are projected into operative position. When thus projected, the legs stand at a slight forward incline, and thus tend to hold the bicycle against casual forward movement, while at the same time affording a stable support to prevent the same from tilting over. The 115 shoe of the pivoted lever when thrown down 120 in the manner described also serves to bear upon the tire of the front wheel and act as a brake to hold the bicycle against casual backward movement. When it is desired to close up the support, the said pivoted lever is 125 thrown upward, and the flexible rod or guide mounted thereon will be thereby drawn forwardly through the medium of the connecting-links. At the same time the hooked rear end 23 of the rod acts on the slotted eccentric or cam link 22 to move the same forwardly, and thus draw the U-shaped oscillatory frame, supporting-legs, and shaft upwardly against the tension of the springs 8,

the legs being guided by the slots until they are closed together and extend parallel with each other and with the tube 26. The forward movement of the tube also causes the 5 trip or striker 36 to spread the two members of the rest or holder apart, so that they will move under and support the legs. The backward movement of the tube which takes place when the pivoted lever is thrown down to 10 project the legs in the manner heretofore described withdraws the trip or striker from engagement with the pivoted members of the rest or holder, which close together by gravity and release the legs. It will be understood from the foregoing description that the 15 connection between the pivoted lever and U-shaped frames—viz., the flexible rod and tube—serves when said lever is thrown up to close the parts against the tension of the 20 springs on the shaft or arbor in the casing and also release the said legs when the lever is thrown down, so that the cross-bar 21, connecting the oscillatory frames, may move freely in the slot of the cam or eccentric link, 25 and thus allow the springs to force the shaft, frame, and legs downwardly.

The tube 26, to which the links are connected, may be readily and conveniently adjusted when desired to adapt the support 30 for application to bicycle-frames of different lengths.

It will of course be understood that changes in the form, proportions, and minor details of construction may be made within the scope 35 of the invention without departing from the nature or spirit of the invention or sacrificing any of the advantages thereof.

Having thus described the invention, what is claimed as new is—

40 1. A bicycle-support, consisting of a casing, an oscillatory shaft journaled in the casing, a pair of frames mounted to oscillate with the shaft, a pair of supporting-legs pivoted to said frames and adapted to swing laterally therein, 45 and a spring or springs acting to normally turn the shaft in a forward direction and thereby swing the legs downwardly and rearwardly, substantially as described.

2. In a bicycle-support, consisting of a casing provided in its bottom with a pair of longitudinal slots having their front ends curved inwardly and their rear ends curved outwardly, an oscillatory shaft mounted in the casing, a pair of frames projecting from the shaft at the front of the casing and mounted to oscillate therewith, supporting-legs pivoted to said frames and adapted to swing laterally therein and projecting through said slots, and springs acting to normally turn the shaft in a forward direction and project the legs downwardly and rearwardly, substantially as described.

65 3. A bicycle-support, consisting of a casing, a spring-actuated oscillatory shaft mounted therein, a pair of frames projecting from the shaft at the front of the casing and adapted to oscillate therewith, a pair of pivoted sup-

porting-legs mounted to swing laterally in said frames and adapted to be normally swung downwardly and rearwardly by the shaft, and 70 means for retracting the shaft, frames and legs against the tension of the springs acting on said shaft, substantially as described.

4. A bicycle-support, consisting of a casing, a spring-actuated oscillatory shaft mounted 75 therein, a pair of frames projecting from the shaft at the front of the casing and adapted to oscillate therewith, a pair of pivoted supporting-legs mounted to swing laterally in said frames and adapted to be normally swung 80 downwardly and rearwardly by the shaft, a slotted oscillatory cam or eccentric link mounted on a rod or cross-bar connecting the frames, and means for acting on said link for retracting the shaft, frames and legs, sub- 85 substantially as described.

5. A bicycle-support, consisting of a casing, a shaft mounted to oscillate therein, springs acting on the shaft to normally turn the same in a forward direction, a pair of substantially 90 U-shaped frames arranged at the front of the casing and mounted to oscillate with the shaft, a cross-bar connecting the frames, a pair of supporting-legs pivoted to said frames and adapted to swing laterally in slots therein 95 and to be swung downwardly and rearwardly when the shaft is turned by the springs, a slotted cam or eccentric link mounted on the cross-bar, and a rod engaging the link for retracting the parts against the tension of the 100 springs, substantially as described.

6. In a bicycle-support, the combination with the frame of a bicycle, of a casing adapted to be secured to the lower main tube thereof, a pair of pivoted supporting-legs, a spring-actuated oscillatory shaft mounted in the casing and adapted to normally project the legs, a pivoted lever adapted to be secured to the head-tube of the frame, a connection between the lever and shaft for retracting the same 110 and folding up the supporting-legs, and an automatically-operated holder adapted to receive and support the free ends of the legs, substantially as described.

7. In a bicycle-support, the combination, 115 with the frame of a bicycle, of a casing adapted to be secured to the lower main tube thereof, a pair of pivoted supporting-legs, a spring-actuated oscillatory shaft mounted in the casing and adapted to normally project the legs, 120 a rod operatively connected with the shaft for retracting the same and folding up the legs, a pivoted lever adapted to be secured to the head-tube of the frame, a pair of links connected at their front ends to the lever, and a 125 slide adjustably mounted on the rod and connecting the rear ends of the links thereto, substantially as described.

8. In a bicycle-support, the combination, 130 with the frame of a bicycle, of a casing adapted to be secured to the lower main tube thereof, a spring-actuated shaft mounted in the casing, a pair of frames mounted to turn therewith, and having a cross-bar, a pair of sup-

porting-legs pivoted to said frames and adapted to be automatically projected by the shaft, a cam or eccentric link connected to said cross-bar, a rod adapted to be slidably supported upon said main tube and connected at its rear end to said link to retract the shaft and frames and fold up the legs, and a lever for operating said rod adapted to be pivotally connected to the head-tube of the frame, substantially as described.

9. In a bicycle-support, the combination with the frame of a bicycle, of a casing adapted to be secured to the lower main tube thereof, a pair of pivoted supporting-legs, a spring-actuated oscillatory shaft or arbor mounted

in the casing and adapted to normally project the legs, a movable rod for retracting the shaft and folding up the legs, a holder or rest comprising a pair of movable members supported from the frame and adapted to receive and hold the legs when the latter are folded, and means coacting with the rod for shifting the members of the holder or rest into position to engage the legs.

In testimony whereof I affix my signature 25 in presence of two witnesses.
